INFLATABLE EMERGENCY TRAFFIC SIGNAL UNIT

Milton Levy, 664 Zola St., Woodmere, Long Island, N.Y., and Phillip Horowitz, 344 Oak Drive, Hewett, Long Island, N.Y.

Filed Aug. 27, 1965, Ser. No. 483,276
7 Claims. (Cl. 116—63)

This invention relates to new and useful improvements in an inflatable collapsible road marker to be used temporarily as a traffic warning signal.

The invention has its outstanding use for emergencies on roadsides by motorists. It is well known that there is a wide-spread need for such a warning signal to be used temporarily to ward off traffic when a motorist is forced by car trouble to park on or adjacent to a traffic lane.

The need for such a warning signal for use by individual motorists is especially great at night, when it is not possible to observe at any great distance the fact that a motorist has stopped because of car trouble. The red danger tail lights may not be visible to an oncoming driver in the night.

One of the major problems existing with the conventional forms of emergency inflatable road markers is that there is usually no fluid or air handy for use in inflating the road marker. Furthermore, difficulty is experienced in finding a sufficiently smooth and level supporting surface upon which to mount the road marker. Often more than one signalling element is needed for signalling for special attention whereas the conventional road marker usually has only a single signalling element.

It is therefore a primary object of the present invention to provide an inflatable signalling device with means for ready attachment to the air valve of the tire of an automobile so as to receive a supply of air from the tire.

Another important object of the present invention is to provide a road marker with suction means whereby the marker may be readily mounted and supported on the surface of the road or on a fixed portion of the vehicle.

Still another important object of the invention is to provide a road marker with an inflatable signalling device as well as with a flexible signalling device.

A further object of the invention is to provide an inflatable road marker that is collapsible into a small and compact package for marketing and for convenient storage when not in use.

Yet another object of the invention is to provide an inflatable road marker that is simple in construction, light in weight and which can be manufactured and sold at a reasonable cost.

For further comprehension of the invention, and of the objects and advantages thereof, reference will be had to the following description and accompanying drawings and to the appended claims in which the various novel features of the invention are more particularly set forth.

In the accompanying drawings forming a material part of this closure:

FIGURE 1 is a perspective view showing a roadside scene with a road marker embodying one form of the invention shown in operative position on the road.

FIG. 2 is a disassembled perspective view of the road marker and showing an air valve actuating member.

FIG. 3 is a sectional view taken on the line 3—3 of FIG. 2.

FIG. 4 is a vertical sectional view taken on the line 4—4 of FIG. 2.

FIG. 4A is a top plan view of the parts of FIG. 4.

FIG. 5 is a perspective view showing the balloon and

2

air valve actuating member connected to the air valve of an automobile tire for inflating the balloon.

FIG. 6 is a sectional view taken on the line 6—6 of FIG. 5.

FIG. 7 is an enlarged horizontal sectional view taken on the line 7—7 of FIG. 5.

FIG. 8 is an enlarged perspective view showing the neck of the balloon wrapped around the supporting post and anchored in a bend in said post.

FIG. 9 is a perspective view of a kit with the cap removed showing the contents of the kit in partially removed condition.

FIG. 10 is a disassembled sectional view of modified means for connecting the supporting post to the suction cup base.

FIG. 11 is a similar view of another modified form of connection.

FIG. 12 is a similar view of still another modified form of connection.

FIG. 13 is a rear elevational view of an automobile with a road marker embodying yet another modified form of the invention installed on the roof thereof.

FIG. 14 is an enlarged side elevational view of the supporting post and suction cup base shown in FIG. 13 with a signalling device supported intermediate the ends of the post.

FIG. 15 is a similar view showing a modified form of collapsible post.

FIG. 16 is a similar view showing another modified form of telescopic post, the post being shown in collapsed condition.

FIG. 17 is a side elevational view of a road marker embodying a still further modified form of the invention, on a reduced scale.

Referring now more in detail to the various views of the drawings, in FIG. 1 a road marker 10 embodying one form of the invention is shown mounted on a roadway 12 at a safe distance from a disabled automobile 14. The road marker is preferably positioned in the middle

40 of the roadway, and is shown mounted on a hubcap 16 of a wheel of the automobile 14 placed flatwise on the road.

The improved road marker 10 comprises broadly a base in the form of a suction cup 18, an elongated upright supporting post 20 of thin round wire, and a rubber balloon 22.

The suction cup 18 has a dished-shaped body 24 with a central enlargement 26 on the outer surface thereof. The enlargement is formed with an annular groove 28.

50 The upright elongated supporting post 20 has an elongated main body section 30 which is formed with a double-bend portion 32 along one side, at one end, the top end as viewed in FIG. 2 and continues upwardly into an auxiliary body section 34 which terminates in a radial finger 36 extending in one direction and formed with a horizontal loop 38. At its other or bottom end, the main body is bent perpendicularly forming a finger 40 extending in a direction opposed to the direction of finger 36, the body continuing downwardly into an auxiliary body section 42 which terminates in a horizontal loop 44

55 extending in the same direction as loop 38.

The balloon 22 has an elongated rubber sac-like body 46 closed at one end, with an elongated restricted neck 48 at its other end. A bead 50 is formed around the opening 52 in the neck. The outer surface of the body is preferably given a coat 53 of light reflective paint, such as red paint.

60 In assembling, the post 20 is mounted on the suction cup 18 by squeezing the loop 44 around the enlargement 26 and slipping the loop into the groove 28. This will support the post in upright position. The balloon 22 is first inflated into spherical form as shown in FIG. 1 and

the neck 48 inserted through the loop 38 at the top of the post and wrapped around the auxiliary body section 34 and the beaded end of the neck anchored in the double-bend 32 as seen in FIG. 1.

In use, when assembled as aforesaid, and the balloon 22 is inflated, the road marker 10 is ready to be mounted in an effective position such as on the roadside 12 sufficiently away from the disabled automobile 14 to warn the oncoming traffic of the danger involved. The road marker 10 may be mounted directly on the surface of the roadside 12 or may be mounted on the hubcap 16 or any smooth surface of the automobile if the roadside is not sufficiently smooth. If the automobile is off of the roadside to one side away from the lane of traffic, the road marker 10 may be mounted on the roof top of the automobile as shown in FIG. 13.

The invention contemplates provision of means for obtaining an emergency supply of air from the tire 55 of the automobile 14 for inflating the balloon 22. For this purpose, a tubular air-valve actuating member 56 is provided for actuating the movable member 58 of a Schraeder valve 60 of the automobile tire 51 as seen in FIG. 7. The actuating member 56 is best seen in FIG. 4 and has an elongated tubular body 62 open at both ends, preferably with one end flaring as indicated at 64. Inside the body, at the other end thereof, there is a flat plate 66 with a central projecting finger 68 thereon extending toward the adjacent open end of the body, and extending to the edge of the said open end. The body serves as a handle for manipulating the actuating member 56.

In order to inflate the balloon 22, the beaded open end of the neck 48 of the balloon is stretched over the flaring end 64 of the actuating member 56 and the other open end of the actuating member sleeved over the protruding end of the air valve 60 of the automobile tire, the valve cap having first been removed, and the movable member 58 of the air valve pressed inwardly releasing the air from the tire and permitting it to flow into the balloon as shown by the arrows in FIG. 7, for inflating the balloon.

Referring particularly to FIG. 9, the invention contemplates marketing the road marker 10 in a kit 70, the contents of which includes the elements of the road marker, an instruction sheet 72 and an extra supply of balloons 22. The kit 70 has a hollow cylindrical body 74 of pasteboard or other suitable material, open at one end and provided with a removable cap 76 therefor. The body 74 has indicia 78 printed thereon.

In FIGS. 10, 11 and 12, modified forms of means for connecting the supporting post 20 to the suction cup 18, in place of the loop 44, is shown.

In FIG. 10, the enlargement 26' is formed with a central socket opening 80 fitted with a bushing 82 to receive the threaded bottom end 84 of the main section 30' of the supporting post.

FIG. 11 shows a headed threaded bolt 86 anchored in the enlargement 26' and projecting upwardly therefrom to receive the socketed internally threaded end 88 of the main section 30' of the supporting post.

In FIG. 12, the enlargement 26'' is shown slightly elongated and provided with a central slightly tapered socket opening 90 to receive the bottom end of the main section 30'' of the supporting post.

In FIGS. 13 and 14, yet another modified form of road marker 10a is shown mounted on the roof of an automobile 14. The marker 10a differs from the road marker 10 merely in the construction of the supporting post 20a. In road marker 10a, the main body section 30a of the post is plain at the bottom and its bottom end extends directly into the enlargement 26a on the suction cup 18a. Furthermore, the main section 30a is formed with a loop 96, intermediate its ends, not provided in road marker 10. The loop 96 provides means for removably supporting an additional signalling device, such as a flexible handkerchief 98 or the like pulled there-

through. The balloon 22a serves to signal that the motorist is in distress, and the handkerchief 98 serves as an additional signal to signal that a certain person is needed, such as a police officer.

In all other respects, the road marker 10a is similar to road marker 10 and similar references are used to indicate similar parts.

In FIG. 15, a modified form of supporting post 20x is shown which differs from the supporting post 20a of FIG. 14 in that the body of the post is sectional and collapsible, being formed with an upper section 100 and a lower section 102 joined by a pivot connection including a loop 104 on the bottom end of the upper section 100 and a coacting pivot pin 105 carried at the top end of the lower section 102. A metal tube 106 is slidably sleeved around the joint and is limited in its downward sliding movement by means of a bend 108 formed in the lower section 102 remote from the joint. The tube 106 moves in the direction of the arrow 110 to permit the upper section 100 to be swung downwardly in the direction of the arrow 112 to permit collapse of the post. The loop is omitted from post 20x.

FIG. 16 illustrates yet another modified form of supporting post 20w which differs from the supporting post 20a of FIG. 14 merely in providing telescopic inner and outer sleeves 114 and 116, respectively, around the main body 30w of the post. This permits the body of the post to be adjusted in length so that the body with the supported balloon may be lowered in case of high winds.

Referring now to the modified form of road marker 10xx shown in FIG. 17, herein the marker comprises a suction cup 18xx, a sectional supporting post 20xx and a balloon 22xx. The suction cup and balloon are similar to the cup and balloon of FIG. 1.

The supporting post 20xx however consists of an upright wire 120 socketed at its lower end in the suction cup 18xx and pivotally connected at its top end to an upright tubular member 122, intermediate the ends of the tubular member, by means of a perforated ear 124 on the tubular member. A one-way valve such as the Schraeder valve 60 of FIG. 7 is mounted in the tubular member. The wire 120 is formed with a laterally extending shelf 126 midway its ends on which is supported a rubber gasket 128. The lower end of the tube member 122 normally seats on the gasket 128, preventing escape of air from the balloon 22xx. The neck 48xx of the balloon is slipped over the top end of the upright tubular member 122. In order to inflate the balloon 22xx, the bottom end of the tubular member 122 is inserted into the flared end 64 of the valve actuating member 56.

While I have illustrated and described the preferred embodiments of my invention, it is to be understood that I do not limit myself to the precise constructions herein disclosed and that various changes and modifications may be made within the scope of the invention as defined in the appended claims.

What is claimed is:

1. An emergency road marker for use by motorists as a traffic warning device comprising, a suction cup having a central enlargement on the outer surface thereof, an elongated wire supporting post, a loop on the bottom end of said wire fastened around the enlargement on the suction cup supporting the post in upright position, a loop on the top end of the wire, a double bend in the wire remote from the top loop, and an inflated balloon with an elongated open neck extending through the top loop and anchored in the double bend.

2. An emergency road marker for use by motorists as a traffic warning device comprising, a suction cup having a central enlargement on the outer surface thereof, an elongated wire supporting post having a main body section, an auxiliary body section at one end, a double bend connecting said main and auxiliary body sections, a loop on the end of the auxiliary body section extending laterally of the main body section, an auxiliary

body section at the other end of the main body section, loop on the end of the latter auxiliary body section extending laterally of the main section, said last-named loop fastened around the enlargement on the suction cup, and an inflated balloon with an elongated open neck extending through said first-named loop, wrapped around the first-named auxiliary body section and anchored in said double bend.

3. An emergency road marker for use by motorists as a traffic warning device comprising, a suction cup having a central enlargement on the outer surface thereof, said enlargement having a socketed opening therein, an elongated upright wire supporting post anchored at its bottom end in the socketed opening in the suction cup, said post having an elongated sectional and collapsible body with an upper section and a bottom section pivotally connected in elongation of each other, a tubular member slidably sleeved over the pivotal connection, means for limiting downward movement of the tubular member, said tubular member adapted to be moved above the pivotal connection whereby the upper section is adapted to be swung downwardly for collapsing the marker, a double bend in the upper section, a loop at the top end of the upper section, and an inflated balloon with an elongated open neck extending through the loop at the top end and anchored in the double bend.

4. An emergency road marker for use by motorists as a traffic warning device comprising, a suction cup having a central enlargement on the outer surface thereof, said enlargement having a socketed opening therein, an elongated upright wire post having its bottom end inserted in the socketed opening in the enlargement, a tubular member forming an extension of the post offset from the plane of the post, means of pivotal connection between the top of the post and midway the ends of the tubular member, a shelf extending laterally of the post midway its ends, a gasket supported on said shelf, the bottom end of the tubular member normally seated on said gasket to seal the bottom end thereof, and an inflated balloon with an elongated neck stretched over the top end of the tubular member.

5. An emergency road marker for use by motorists as a traffic warning device comprising, a suction cup having a central enlargement on the outer surface thereof, an elongated wire supporting post supported in upright position on said enlargement, a loop on the bottom end of said wire fastened around the enlargement on the suction cup, an inflated balloon with an elongated open neck removably fastened to the top of the wire, and means in common for connecting the neck of the balloon to the air valve of an automobile tire and for actuating said valve, said means including a tubular member open at both ends and a flat plate anchored inside one end of the tubular member, with plate having a projecting finger extending to the edge of the adjacent open end of the body of the tubular member adapted to engage the movable member of the air valve of an automobile tire for releasing the air from the tire.

6. As an article of manufacture, a device for connecting the open neck of a rubber balloon to the air valve member of the tire of an automobile and for actuating

the movable member of the said valve member, said device consisting of a tubular member open at both ends, and a flat plate inserted inside the tubular member at one end thereof, said plate having a finger extending toward the adjacent end of the tubular member for engagement with the movable member of an air valve member of a tire of an automobile.

7. A kit of the kind described comprising an elongated hollow cylindrical pasteboard container having one end closed, the other end being open, a removable cap for the open end, a plurality of elongated rubber balloons inside the body of the container, said balloons having elongated open necks, a suction cup with an enlargement on the central outer surface thereof in said container, said enlargement having a socketed opening therein, an elongated wire in said container formed with a perpendicular loop at one end and with a double bend adjacent said loop, the other end of the wire being smooth and an instruction sheet therein.
